Donald H. Mitchell, Chicago, Ill., assignor to Gal-
vin Manufacturing Corporation, Chicago, Ill.,
a corporation of Illinois

Application February 12, 1937, Serial No. 67,622

Term of patent 7 years

To all whom it may concern:

Be it known that I, Donald H. Mitchell, a citizen of the United States, residing at Chicago, in the county of Cook and State of Illinois, have invented a new, original, and ornamental Design for a Control Device for Radio Receivers, of which the following is a specification, reference being had to the accompanying drawing, forming part thereof, in which:

Figure 1 is a perspective view of my design for a control device for radio receivers, and
Figure 2 is an end elevation thereof.

I claim:

The ornamental design for a control device for radio receivers as shown.

DONALD H. MITCHELL.
